UNITED STATES PATENT OFFICE

CLARENCE F. WARD, OF BIRMINGHAM, ALABAMA

PIPE LAYING APPARATUS

Application filed May 1, 1931. Serial No. 534,408.

My invention consists in new and useful improvements in a pipe laying apparatus and has for its object to provide a device for supporting a string of connected pipe sections above the ground while painting, cleaning, wrapping or otherwise preparing said pipe for lowering into a ditch, in such a manner as to avoid injury to the pipe or protective coating which may have been applied thereto.

Another object of my invention is to provide an apparatus which in itself is portable and adapted to be moved longitudinally alongside of a ditch and at the same time supporting the underside of a portion of the string of pipe, progressively lifting that portion of the string which has been prepared alongside the ditch and lowering it into the ditch.

A further object of my invention resides in my improved carriage or conveyor which consists of a suitable endless belt or the like adapted to freely rotate around a plurality of rollers and provided with a series of brackets for successively engaging and supporting the under-surface of the pipe as the apparatus moves along longitudinally of the pipe.

A still further object of my invention is to provide each bracket with a flexible transverse sling arranged and constructed to automatically assume the contour of the pipe resting thereon, means being provided for adjusting the tension of said slings to suit different sizes of pipe with which the device may be employed.

With the above and other objects in view which will appear as the description proceeds, my invention consists in the novel features herein set forth, illustrated in the accompanying drawings, and more particularly pointed out in the appended claims.

Referring to the drawings in which numerals of like character designate similar parts throughout the several views,

Fig. 1 is a plan view of the device in operation showing the manner in which the string of pipe is lifted from alongside the ditch and lowered therein.

Fig. 2 is a sectional view taken on line 2—2 of Fig. 1, showing the supporting derrick

diagrammatically and illustrating the relative positions of the carriage, pipe and ditch.

Fig. 3 is a view in side elevation showing the conveyor belt and pipe supporting brackets.

Fig. 4 is a sectional view taken on line 4—4 of Fig. 3, and

Fig. 5 is a reduced vertical sectional view taken on line 5—5 of Fig. 1. It will be noted that this view is greatly exaggerated to accentuate the operation of the invention and is not intended to be correct in proportions.

In the drawings, 1 represents a conventional derrick having a caterpillar traction base 2 and the usual boom 3, the latter supporting my improved pipe carriage by means of a cable 4 which passes over the pulley 5 and is reeled upon any suitable winch or the like.

The pipe carriage comprises a frame 6 preferably constructed of a pair of longitudinally extending channel irons spaced apart laterally and carrying at least two rollers 7 arranged one at each end of the frame. It will be noted that while I have shown only two rollers in the frame 6, this is merely for the purpose of illustration and any additional number of rollers may be employed as required.

An endless belt or conveyor 8 which may be composed of canvas, rubber, composition belting, metallic links or caterpillar treads, extends around the rollers 7 and is adapted to travel freely thereover. This belt is provided with a plurality of transverse brackets 9 rigidly secured in place by any suitable means and arranged at spaced intervals throughout the length of the belt on its outer surface, said brackets each carrying two pivoted arms 10, bifurcated at their lower extremities to straddle the brackets 9 and hingedly secured in place thereon by suitable pins 11.

The upper ends of the arms 10 are preferably flared longitudinally of the frame and are also bifurcated to receive the ends of a sling 12, said sling ends being looped around a suitable rod or pin 13 which extends between the upper bifurcations of the arms 10. The tension of the slings 12 is adjustable to

suit different sizes of pipes, by means of set screws 14 which extend transversely through the arms 10 with their inner extremities in abutment with suitable stops or lugs 15 rigidly secured on the brackets 9, whereby the relative positions of the arms 10 may be varied. In other words, for a pipe of large diameter, the arms 10 are adjusted to their extreme diverging positions, while for a pipe of small diameter, said arms are permitted to swing inwardly toward one another to the required degree.

The frame 6 may be supported by any suitable means, but for the purpose of illustration, I have shown supporting loops or bales 16, the lower extremities of which are secured to the frame 6 as at 17, while the uppermost points of the loops are bent as at 18 to engage a suitable hook 19 on the cable 4, whereby the entire frame and carriage may be supported over a ditch 20 by the boom 3 of the derrick 1 as clearly shown in Fig. 2.

It will be noted that the string of pipe 21 is progressively supported by the uppermost set of slings 12 and as the carriage is moved along longitudinally of the pipe, the arms and slings carried thereby are successively brought into and out of engagement with the under-surface of the pipe by the rotation of the endless belt 8 around the rollers 7.

Having thus described the construction of my improved pipe laying device, its operation is as follows:—

Referring to Figs. 1 and 5 of the drawings, the sections of pipe are connected along the side of the ditch as at 22, anterior to the point of engagement by the carriage. The string of pipe extends over the carriage and rests upon the uppermost slings 12, which portion of the pipe is elevated as shown in Fig. 2, which permits the pipe to be painted, wrapped, cleaned or otherwise prepared for lowering in the ditch. As the work of preparation progresses, the derrick 1 is moved longitudinally of the ditch in the direction of the arrow in Fig. 1 and as it moves, the pipe remains longitudinally stationary, the belt 8 and with it the arms 10 and slings 12 revolving around the rollers 7, said slings successively assuming new positions along the under-surface of the pipe as the belt rotates. That portion of the pipe posterior to the carriage is gradually lowered into the ditch as the derrick and carriage move along until the entire string of pipe has been treated and lowered into the ditch.

It will be noted that while I have described a derrick with caterpillar traction apparatus, the derrick may be mounted on wheels and the pipe carriage may be otherwise conveniently supported and operated by any suitable source of power. Furthermore, it is obvious that instead of the rollers 7, I may employ sprocket wheels or the like for rotatably supporting the conveyor belt or element 8.

From the foregoing it is believed that the construction, operation and advantages of my improved pipe laying apparatus may be readily understood by those skilled in the art without further description, it being borne in mind that numerous changes may be made in the details of construction without departing from the spirit of the invention as set forth in the following claims.

What I claim and desire to secure by Letters Patent is:—

1. Apparatus for laying pipe lines comprising a frame, an endless conveyor operatively carried on said frame, means on said conveyor for progressively engaging a portion of the under-surface of a pipe line, means for suspending said frame over a ditch, and means for moving said frame longitudinally of said ditch under said pipe line.

2. In apparatus for laying pipe lines, a pipe supporting carriage comprising a frame, a plurality of rotary members carried by said frame, an endless conveyor mounted to travel over said rotary members, and a series of pipe supporting elements secured to said conveyor and adapted to successively engage the under-surface of a portion of a pipe line as said conveyor travels over said rotary members.

3. In apparatus for laying pipe lines, a pipe supporting carriage comprising a frame, a plurality of rotary members carried by said frame, and endless conveyor mounted to travel over said rotary members, a series of pipe supporting elements secured to said conveyor and adapted to successively engage the under-surface of a portion of a pipe line as said conveyor travels over said rotary members, and means for adjusting said pipe supporting elements to accommodate various sizes of pipes.

4. In apparatus for laying pipe lines, a pipe supporting carriage comprising a frame, a plurality of rotating members carried thereby, an endless conveyor mounted to travel over said rotating members, a series of upwardly projecting arms mounted on said conveyor in pairs, and transverse slings carried between each of said pairs of arms for successively supporting the under-surface of a portion of a pipe line as said frame travels longitudinally under the same.

5. In apparatus for laying pipe lines, a pipe supporting carriage comprising a frame, a plurality of rotating members carried thereby, an endless conveyor mounted to travel over said rotating members, a series of upwardly projecting arms mounted on said conveyor in pairs, transverse slings carried between each of said pairs of arms for successively supporting the under-surface of a portion of a pipe line as said frame travels longitudinally under the same, and means for adjusting the tension of said slings to accommodate various sizes of pipes.

6. In apparatus for laying pipe lines, a

pipe supporting carriage comprising a frame, a plurality of rotating members carried thereby, an endless conveyor mounted to travel over said rotating members, a series of upwardly projecting arms mounted on said conveyor in pairs, transverse slings carried between each of said pairs of arms for successively supporting the under-surface of a portion of a pipe line as said frame travels longitudinally under the same, said arms being pivotally mounted on said conveyor, and means for adjusting their relative positions to regulate the tension of said slings to accommodate various sizes of pipes.

7. In apparatus for laying pipe lines, a pipe supporting carriage comprising a frame, a plurality of rotating members carried thereby, an endless conveyor mounted to travel over said rotating members, a series of brackets rigidly secured to the outer surface of said conveyor, upwardly projecting arms pivotally mounted on said brackets and arranged in pairs transversely of said conveyor, pipe engaging slings carried between each of said pairs of arms, and means for adjusting the relative positions of said arms to regulate the tension of said slings for accommodating various sizes of pipes.

8. Apparatus as claimed in claim 7 wherein said adjusting means comprise set screws projecting through said arms and adapted to abut lugs rigidly mounted on said brackets, whereby said arms may be adjusted on their pivots to the desired position.

9. In combination with a derrick having suitable traction means, pipe laying apparatus comprising a frame, means for suspending said frame from the boom of said derrick over a ditch, a plurality of rotating members carried by said frame, an endless conveyor mounted to travel over said rotating members, a series of pipe supporting elements mounted on said conveyor and adapted to successively engage the under-surface of a portion of a pipe line, whereby when said derrick is moved longitudinally of said ditch, said conveyor will travel around said rollers, the pipe supporting elements progressively engaging and supporting portions of the under-surface of said pipe line.

In testimony whereof I affix my signature.

CLARENCE F. WARD.
